UNITED STATES PATENT OFFICE.

HENRY E. MAURER, JR., OF SPRINGFIELD, ILLINOIS, ASSIGNEE, BY DIRECT AND MESNE ASSIGNMENTS, OF ONE-THIRD TO HARRY L. IDE AND ONE-THIRD TO R. W. IDE, BOTH OF SPRINGFIELD, ILLINOIS.

APPARATUS FOR DISPENSING LIQUIDS.

1,261,491.

Specification of Letters Patent.

Patented Apr. 2, 1918.

Application filed November 1, 1916. Serial No. 130,949.

To all whom it may concern:

Be it known that I, HENRY E. MAURER, Jr., a citizen of the United States, residing at Springfield, in the county of Sangamon and State of Illinois, have invented a new and useful Apparatus for Dispensing Liquids, of which the following is a specification.

This invention relates to means adapted to dispense liquids in such manner that the purchaser may see for himself that he is actually getting the quantity for which he is paying.

The purposes of the invention are: to provide in conjunction with a vessel for containing the liquid, means for exhausting air from the vessel, means for conveying liquid into the vessel, means for admitting air into the vessel above the liquid, and means for controlling discharge of the liquid from the vessel; to provide sealable gages in connection with the containing vessel; to provide in conjunction with a transparent container a perforated cover adapted to protect the container and a lamp adjacent to the cover and adapted to illuminate the container by the light passing through the perforations of the cover and through the transparent wall of the container; to provide a vacuum chamber in controlled communication with the interior of the container; to provide means for maintaining a working vacuum in the vacuum chamber; and to provide other features of construction which will be described later.

The invention is illustrated in the annexed drawings, to which reference is hereby made and will be hereinafter described and finally recited in the claims.

Figure 1 is a front elevation of an apparatus of preferred construction; Fig. 2 is a top plan, Fig. 3 is a vertical section on the line 3, 3, of Fig. 1. Fig. 4 is a diagram of a container of modified construction comprising a vessel of opaque material provided with a transparent graduated front plate. Fig. 5 is a diagram of an opaque container provided with an external graduated gage, and Fig. 6 is an enlarged isometric view of one of the sealed gage bands. The same reference numerals designate the same parts in the different views.

The apparatus herein shown and described is primarily designed for vending gasoline,

but my invention contemplates and includes apparatus for vending other liquids, such as milk, vinegar, cider, etc.

The main structure is preferably of sheet metal and comprises an air tight basal casing 1, serving as a vacuum chamber, and an upper casing 2, mounted on the casing 1 and adapted to support the container and adapted to conveniently house the operating mechanisms. The casing 2 has at its lower end a flange 3 fitting around the upper end 65 of the basal casing 1, and has at its upper end wells 4 adapted to accommodate the containers 5. The containers 5 are preferably of glass, or other transparent material, but obviously may be partly of opaque material 70 and partly of transparent material, as shown in Fig. 4; or may be wholly of opaque material and provided with external transparent gages as shown in Fig. 5.

The containers 5 are preferably inverted 75 glass bottles seated in the wells 4 of the casing 2. The bottoms of the bottles, which become the tops of the containers when the bottles are inverted, are internally concave as shown, for a purpose which will be explained later.

The covers 6 are concaved to conform to the upper ends of the containers 5 and have openings 7, through which light is admitted to the interior of the containers 5. 35

Lamps 8, stationary on the covers 6, furnish light to illuminate the containers as occasion may demand. Rods 9 connect the covers 6 with the top of the casing 2, so that the covers will firmly hold the containers 5 in the wells.

The necks of the containers preferably have screw threads 12. T-couplings 10 screw onto the threads 12 to connect the couplings with the containers. Intake pipes 13 screw into the lower ends of the T-couplings and extend downward through the vacuum chamber 1 into the tank 14 containing the supply of gasoline. Supply pipes 15 screw into the T's 10 in line with the upper terminals of the intake pipes 13 and extend upward within the containers 5. Vacuum tubes 16 are inside of the pipes 15 and extend upwardly beyond the upper ends of the pipes. The supply pipes 15, within the containers 5 are of such length that when the maximum measured quantity of liquid (in the present case say five gallons in each con-

tainer) is in the containers the upper ends of the pipes 15 in the containers will be in the plane of the upper surface of the liquid in the containers. The concavities 34 at the 5 upper ends of the containers admit of extending the tubes 16 a considerable distance upward above the pipes 15, in order that when the vacuum in the tubes 16 is effective to draw the liquid upward through the pipes 15, the liquid will rise above the upper ends of the pipes 15, and immediately upon admission of air through the tubes 16, the surplus liquid will flow downward through the pipes 15 into the tank 14, and the upper 10 surface of the liquid in both containers will be in the plane of the upper ends of the pipe 15 and there will be exactly the same maximum quantity of liquid in each container.

Lateral tubes 17 at the lower ends of the 20 tubes 16 intercommunicate with the tubes 16 and with the tubes 18 which communicate with the interior of the vacuum chamber 1.

Cocks 19 in the tubes 18 control the 25 vacuum in the tubes 16. Air cocks 20 control the admission of air to the tubes 16 when the cocks 19 are closed. A pump 21 preferably actuated by a motor 22, of any approved type, serves to exhaust air from 30 the tank 1 and maintain a working vacuum in the tank.

Outlet pipes 23 screw into the T's 10 and the pipes are in communication with a cross pipe 24, through valves 25, which control 35 the discharge of liquid through the respective pipes 23. A hose 26 is suitably connected with the cross pipe 24 and conveys away the liquid discharged from the pipes 23.

40 Adjustable gage bands 27 have enlarged terminal members 28 adapted to slide on vertical guides 29 adjacent and parallel to the containers 5.

Bolts 30 serve to secure the members 28 45 on the guides 29 in such position that the respective gage bands will correctly indicate the quantity of liquid which has been taken out of the containers when the liquid remaining in the containers rests at the 50 levels indicated by the upper edges of the respective gage bands. Holes 31 (Fig. 6) in the nuts 33 and the bolts 30 accommodate the wires 32 of seals 33. When the wires are placed in the holes and sealed, it is obvious 55 that the positions of the gage bands cannot be changed without breaking the seals. The invention contemplates official inspection and sealing of the apparatus to the end that the buyer may know that he is receiving the full quantity of liquid to which he is entitled.

The operation is as follows:

The pump 21 will be operated to exhaust air from the vacuum chamber 1 and maintain 60 an effective vacuum therein. To fill

the containers the valve 19 will be opened to induce vacuum in the containers 5, whereupon liquid from the tank 14 will be drawn through the pipes 15 into the containers 5 and will attain a level somewhat 70 above the upper ends of the pipes 15. The valves 19 will then be closed and the cocks 20 will be opened to admit air above the liquid in the containers to cause the surplus liquid to flow downward through the pipes 75 into the supply tank 14, and the containers will then contain the exact measured quantity of liquid, in the present case five gallons in each container; the valves 25 and the hose 26 may then be used to draw off 80 the liquid as required.

It will be noted that in practice one container may be filling while the other is being emptied. It will also be noted that in case a quantity greater than the contents of one 85 container is wanted, the entire contents of one container and part of the contents of the other container may be used.

In the drawings I have shown an apparatus comprising two containers in communication with one vacuum chamber, but it is obvious 90 that a greater number, or a less number, of containers may be used without departure from my invention.

I have shown a motor driving a pump to 95 maintain the vacuum in the vacuum chamber, but my invention contemplates any suitable means for maintaining the vacuum.

I do not restrict my claims to the precise construction shown and described, since it 100 is obvious that minor details of construction may be varied without departure from the spirit and scope of my invention.

What I claim as new and desire to secure by Letters Patent is:

105 1. In an apparatus for dispensing liquids, in combination with an air tight container; a stationary supply pipe inside the container, a vacuum tube inside the supply pipe and adapted to induct liquid through the supply pipe to a level above the upper end of the supply pipe, and means for admitting air through the vacuum tube into the container to permit the surplus liquid above the upper end of the supply pipe to 110 flow outward through the supply pipe, to cause the highest level of vendible liquid to coincide with the horizontal plane of the upper end of the supply pipe.

115 2. In an apparatus for dispensing liquids, 120 the combination of a tank, a container, a stationary supply pipe in communication with the tank and having its upper terminal inside the container and in the plane of the highest level of the predetermined 125 maximum volume of liquid dispensable from the container at any one time, a vacuum tube within the supply pipe and having its upper terminal above the upper terminal of the supply pipe, and means for admitting 130

air to the vacuum tube to cause any excess of liquid inducted into the container to flow through the supply pipe back to the tank, to automatically determine the highest level of vendible liquid in the container.

3. Liquid dispensing apparatus including a liquid container in the form of an inverted glass bottle; a cover for the top of the container having an opening through which light may pass to the container; and a lamp

arranged to direct light through said opening in the cover upon the container.

In witness whereof I have hereunto signed my name at Springfield, Illinois, this 25th day of October, 1916.

HENRY E. MAURER, JR.
